REFRIGERATION SYSTEM

Paul F. Shivers, Wabash, Ind., assignor to Minneapolis-Honeywell Regulator Company, Minneapolis, Minn., a corporation of Delaware

Application June 27, 1934, Serial No. 732,637

31 Claims. (Cl. 62—8)

The present invention relates to improvements in automatic refrigerating systems.

Refrigerating systems can be classified into two groups, one of which is commonly termed "dry expansion systems" and the other of which is generally termed "flooded systems". In a dry expansion system, the expansion or cooling coils are only partially filled with liquid refrigerant, the remainder of the coils being filled with refrigerant in a gaseous state. In flooded systems, the expansion or cooling coil is maintained full of liquid refrigerant. In order to provide a flooded system, it has been common practice to provide a header or surge drum to which is connected a plurality of cooling or expansion coils, both ends of such coils being connected to the surge drum. The surge drum is partially filled with liquid, and all of the cooling coils are completely filled with liquid. As the liquid absorbs heat and is changed into a gas, the gas bubbles up through the liquid in the surge drum and returns to the suction side of the compressor. The surge drum is further provided with a float which responds to the level of the liquid in the surge drum and controls the flow of liquid to the surge drum from the condenser or liquid receiver through a suitable valve.

These flooded systems are known to be very efficient but have the disadvantage of requiring the complicated mechanism above described. In other words, it has heretofore only been possible to provide a flooded system by providing a complicated unit including the expansion or cooling coils, the surge drum and the float valve mechanism, it being impossible by the apparatus heretofore known to change over a dry expansion system to a flooded system or to operate a simple expansion or cooling coil on the flooded principle without making the expansion coil a part of a complicated unitary structure.

Furthermore, in order to operate a plurality of cooling or expansion coils operating on either the dry expansion or flooded principle from a single compressor wherein it is desired to maintain two or more of the expansion or cooling coils at different temperatures, it has been necessary to provide additional mechanism in the form of a suction or back pressure operated snap action valve for each expansion coil or to provide a valve in the suction line for each expansion coil which is operated by the temperature of the associated compartment or device to be cooled by such expansion coil.

One of the objects of the present invention is the provision of a flooded or substantially flooded

refrigeration system which does not require a float mechanism of any type and which can be applied to existing expansion or cooling coils operating upon the dry expansion principle, as well as being applicable to any simple expansion coil, whereby the operating advantages of a flooded system may be obtained substantially while eliminating the mechanical and constructional complications and limitations thereof.

A further object of the invention is the provision of a unitary valve mechanism, which does not include any float structures whatsoever, that is adapted to be applied to any simple expansion coil so as to operate the same on a flooded principle and maintain the proper coil temperature without any additional mechanism, even though the coil be one of a group of coils operated from a single compressor and at different coil temperatures.

Another object of the invention is the provision of a valve that is controlled by the conjoint action of the back pressure and the temperature of the refrigerant on the suction side of the expansion coil in such manner that the valve is not only normally operated by the thermostat to maintain the expansion coil in a flooded condition but is also closed, irrespective of whether or not the coil be flooded, when the back pressure falls to a predetermined value indicating that the desired average coil temperature has been established.

A further object of the invention is the provision of a refrigeration valve mechanism including a suction line valve that is controlled conjointly by the suction pressure and by a single thermostat responsive to the temperature of the refrigerant in the suction line, this single thermostat also operating an expansion valve on the inlet side of the expansion coil.

Another object of the invention is the provision of a thermostatic expansion valve in which the expansion valve is not only controlled by a thermostat, but which is automatically conditioned for such control only at such times that the high side pressure is sufficient to provide proper operation of the cooling coil.

Other objects of the invention will be found in the drawing, the detailed description, and the appended claims.

For a more complete understanding of the invention, reference may be had to the following description and the accompanying drawing, in which:

Fig. 1 is a diagrammatic showing of a refrigerating system with my improved valve mech-

anism applied thereto, the valve mechanism being shown in section and upon an enlarged scale, and

Fig. 2 is a reduced size section of the valve mechanism taken about on line 2-2 of Fig. 1.

Fig. 3 is a fragmentary sectional view taken on line 3-3 of Figure 1.

Referring to the drawing, the system of the present invention includes a valve mechanism generally indicated at 10 which includes an upper casting 11 and a lower casting 12 which are secured together by suitable means, such as the screws 13. Interposed between the upper casting 11 and the lower casting 12 is a sealing member 14 and a pair of suitable gaskets 15. The upper and lower castings 11 and 12, together with other mechanism to be hereinafter described, form a high pressure inlet chamber 16, a control chamber 17, a low pressure inlet chamber 18, and a low pressure outlet chamber 19.

The lower casting 12 is provided with a boss 20 having an internally screw-threaded bore 21 which receives an outlet valve plug 22, there being suitable packing 23 interposed therebetween.

25 The valve plug 22 is provided with a valve opening 24 with which a needle valve 25 cooperates. The valve plug 22 is provided with an extension 26 which serves to guide the needle valve 25. The needle valve 25 is provided with a valve stem 30 27, of reduced diameter, the extended end of which is formed with an enlarged head 28 which is adapted to abut, under certain conditions, the bellows head 29 of a bellows 30. The open end of the bellows 30 is secured to an annulus 31 35 which is sealed to shoulders 32, formed by an opening in the upper casting 11, as by means of soldering. A plate 33, which is secured by screws 34, closes off the interior of bellows 30. The bellows 30 is normally expanded by means of a relatively heavy coiled expansion spring 35 so that valve 25 normally closes the valve opening 24. One end of spring 35 abuts bellows head 29 whereas its other end abuts a spring retainer 36 which is positioned by a screw 37.

40 An actuator comprises a pair of levers 38 and 39, which are held in spaced relation by means of spacers 40 and 41 and are pivoted upon a pin 42 that is journaled in the lower casting 12. The pin 42 is held in place by an enlarged screw-threaded portion 43 thereof which is received by suitable screw threads formed in a boss 44 of the lower casting 12. The extended ends of the members 38 and 39 straddle the guide extension 27. A combined collar and spring retainer 45 45 surrounds the valve stem 27 and is pressed into engagement with the extended ends of levers 38 and 39 by means of a relatively light coil spring 47, one end of which abuts the collar 45 and the other end of which abuts the enlarged head 28 of valve stem 27. Another coil spring 48, of intermediate strength, surrounds the head 28 of valve stem 27 and the coiled spring 47, and has one of its ends abutting the collar 45, whereas its other end abuts the bellows head 29.

50 When the levers 38 and 39 are in a substantially horizontal position and when the bellows head 29 is subjected to a low or atmospheric pressure, the stronger spring 35 partially compresses the spring 48 and holds valve 25 in its closed position. If the left-hand ends of levers 38 and 39 are moved downwardly, the collar 45 is lifted and the spring 48 is compressed, the bellows head 29 remaining stationary so that valve 25 remains in its closed position. Now, if the bellows 75 head 29 is subjected to a predetermined pressure,

it moves upwardly compressing spring 35, whereupon springs 47 and 48 expand, the spring 47 in expanding lifting the valve 25 and moving the same to open position. The expansion of spring 48 continues as long as bellows head 29 continues to move upwardly; but expansion of spring 47 and lifting of valve 25 is limited by engagement of the valve 25 with the collar 45. If the left-hand ends of levers 38 and 39 are now moved upwardly so as to lower the right-hand ends thereof, the collar 45 moves the valve 25 downwardly under the action of spring 48 to an extent determined by the downward movement of the right-hand ends of levers 38 and 39, or until valve 25 completely closes the valve opening 24. In this manner, when the bellows head 29 is raised by being subjected to the proper pressure, the valve 25 is positioned in accordance with the movements of the levers 38 and 39. Whenever the pressure acting upon the bellows head 29 is released, the strong spring 35 moves the bellows head downwardly against spring 48, and against spring 47 if the valve 25 is raised, so as to close the valve. In other words, the arrangement thus far described provides a valve, the action of which is dominated by a pressure responsive member in the form of the bellows head 29 so that the valve is held closed whenever the pressure responsive member is subjected to less than a predetermined pressure, but when the pressure responsive member is subjected to a larger pressure, the valve may be opened or closed in accordance with the movements of the levers 38 and 39. The movements of levers 38 and 39 are controlled by mechanism now to be described.

55 A pair of bellows 50 and 51 have their open ends sealed to the sealing member 14. The upper bellows 50 extends into the low pressure outlet chamber 19 and is provided with a head 52. The lower bellows 51 extends into the control chamber 17 and is provided with a head 53, the arrangement being such that the bellows 50 and 51 form an enclosed expansible chamber 54. The head 53 is provided with a boss 55 and the head 45 52 is provided with a boss 56 which serve to position a cylindrical guiding member 57 that also limits the minimum length of the chamber 54 upon contraction of bellows 50 and 51 or either of them. Surrounding the guiding member 57 is 60 a coiled compression spring 58, one end of which abuts the bellows head 52 and the other end of which abuts the bellows head 53. The bellows head 52 is further provided with an opening 59 through which a suitable charge of volatile fluid 55 may be admitted to the chamber 54, after which the opening 59 is sealed off as by a set screw 60. The bellows 50 and 51 and the spring 58, together with the charge of volatile fluid in the chamber 54 formed thereby, therefore comprise a thermodynamic element.

65 The lower end of lower casting 12 is open and receives a bellows 65, the open end of which is sealed to an annulus 66 that is in turn sealed to the lower casting 12. A cap 67 closes off the 65 interior of bellows 65. The bellows 65 is provided with a bellows head 68 which has a screw threaded extension 69 that is adapted to be threaded into the bellows head 53 of bellows 51. The levers 38 and 39 extend through an opening 70 formed 70 in the lower casting 12 and straddle the extension 69, so that they are disposed between the bellows heads 53 and 68. A coiled spring 71 has one of its ends abutting the inner surface of bellows head 68 and its other end abutting a 75

spring retainer 72 which may be adjustably positioned by means of a screw 73 that passes through the cap 67 in screw-threaded relation therewith.

The upper casting 11 is provided with a partition wall 75 which separates the low pressure inlet and outlet chambers 18 and 19, this partition wall 75 being provided with a valve opening 76. A cooperating valve disc 77 is threaded upon an extended portion of bellows head 56, and under certain conditions abuts the bellows head 78 of a bellows 79. The bellows 79 has its open end sealed to an annulus 80 which is suitably sealed to the upper casting 11. A cap 81 closes off the interior of bellows 79. A coiled spring 82 has one of its ends abutting the inner face of bellows head 78 and its other end abuts a spring retainer 83, the position of which may be adjusted by a screw 84 which is threaded into the cap 81.

This valve mechanism 10 is adapted to be utilized in conjunction with a refrigeration system which includes a compressor 90 that is operated by a compressor motor 91. The compressor 90 is adapted to compress the hot gaseous refrigerant in the usual known manner, after which it is transmitted to a condenser 92 by means of a pipe 93. The condenser 92 is provided with a suitable cooling coil indicated at 94. The condenser 92 serves to condense the compressed gaseous refrigerant and transforms it into a liquid, after which it passes to a liquid receiver 95 by means of a pipe 96. The liquid from liquid receiver 95 is transmitted by a pipe 97 to the high pressure chamber 16, the pipe 97 being connected to a suitable boss 98 formed in the lower casting 12. The outlet valve plug 22 is connected to an expansion or cooling coil 99 by means of a pipe 100. The other end of the expansion coil 99 communicates with the low-pressure inlet chamber 18 by means of a pipe 101 which is connected to a suitable boss 102 formed in the upper casting 11. The low pressure outlet chamber 19 communicates with the compressor 90 by means of a pipe 103 which is connected to a boss 104 formed in the upper casting 11.

The compressor motor 91 is adapted to be controlled by a pressure switch, generally indicated at 105, which includes a mercury switch 106 that closes when the return pressure in line 103 reaches a predetermined high value and opens when the pressure therein is reduced to a predetermined minimum, the setting of this switch 106 depending upon the average temperature it is desired to maintain in coil 99 or in the coldest coil if a plurality of coils are used. The circuit for compressor motor 91 includes line wire 107, mercury switch 106, a wire 108, motor 91, and line wire 109.

Operation

With the parts in the position shown, the supply of electrical power to the compressor motor 91 is disconnected so that the system is completely shut down and not operating automatically. As a result, there is no pressure on the high side of the system, and the spring 35 is therefore able to extend the bellows 30 so that the valve 25 is closed as hereinbefore described. The low side temperature is also high so that the biasing effect of the expansion of the volatile fluid in chamber 54 and the expansive force of spring 58 hold valve disc 77 in open position against the action of spring 82 and also move the right hand ends of levers 38 and 39 upwardly

against the force of springs 71, 47, and 48. The collar 45 is therefore raised out of engagement with the valve 25.

Because of the high back pressure, the back pressure switch 106 is in closed position. If the main switch (not shown) is now closed, the system will be ready to operate under automatic control. The compressor motor 91 will thereupon be energized by the circuit given above. The compressor 90 is thereby operated to compress the gaseous refrigerant which is thereupon transmitted to the condenser 92 through pipe 93. The condenser 92 liquefies the gaseous refrigerant, after which it passes to receiver 95 by pipe 96, the hot liquid thereafter passing to the high pressure inlet chamber 16 by way of pipe 97. As this high side pressure increases, the bellows head 29 is moved upwardly against the action of spring 35. The spring 47 causes the head 28 of valve stem 27 to follow the bellows head 29 thereby opening the valve 25. The valve 25 continues to open as the bellows head 29 continues to move upwardly under the increase in pressure on the high side until such time as the valve 25 engages the collar 45. The liquid refrigerant also passes through opening 10 and into control chamber 17. It exerts equal forces against bellows head 53 and 68, which are of equal size, so that the positions of levers 38 and 39 are not affected by the pressure of the liquid refrigerant. Liquid refrigerant now passes to the cooling coil 99 by way of pipe 100 wherein it evaporates in lowering the temperature of the compartment being controlled. The evaporated liquid passes into low pressure inlet chamber 18 and through the valve opening 76 to the low pressure outlet chamber 19, from which it returns to the compressor by pipe 103. During the starting of the system, the gas returning from the cooling coil 99 will be at a relatively high temperature and pressure, so that the valve disc 77 will remain in open position. The continued feeding of liquid to the cooling coil 99 will soon fill this coil and cause the liquid to pass through the low pressure inlet chamber 18 and into the low pressure outlet chamber 19, whereupon the volatile fluid in the upper portion of chamber 54 will be cooled and the pressure in chamber 54 reduced. This reduction in pressure is supplemented by the action of spring 82 to overcome the expansive force of spring 58, whereupon valve disc 77 is moved toward closed position by the contraction of bellows 50. Likewise, contraction of bellows 51 under the action of spring 71 moves the right hand ends of levers 38 and 39 downwardly to permit spring 48 to lower collar 45 and partially close valve 25. In this manner, the thermostat comprised by the bellows 50 and 51 and the charge of volatile fluid therein contained controls the valve disc 77 and the valve 25 to establish such a flow of refrigerant through cooling coil 99 as to maintain the temperature of the thermostat at the proper and desired point whereby the expansion or cooling coil 99 is normally maintained flooded.

As the temperature of the compartment to be controlled is lowered, the back pressure on the cooling coil 99 and in the low pressure inlet chamber 18 is reduced. If this back pressure should reach a predetermined low point indicating that the temperature of the compartment being controlled has been lowered to the desired point, this lowering in pressure operating against bellows head 78 permits spring 82 to exert a greater force against the valve disc 77, whereupon

the valve disc 17 will be moved toward closed position and will close when the back pressure decreases to a value indicating that the compartment being controlled is at the desired temperature irrespective of the temperature of the thermostat comprised by bellows 50 and 51. Whenever the pressure in suction line 103 becomes lower than the predetermined minimum, the switch 106 will open to deenergize compressor motor 91 until the pressure in suction line 103 rises to the desired maximum.

In this manner, the bellows 79 and its associated spring 82 operate to close valve disc 17 at a predetermined back pressure indicating that the compartment temperature has been lowered to the proper value. As long, however, as the back pressure is higher than that back pressure which indicates the compartment temperature is at the desired value, the thermostat operates to position the outlet valve disc 17 and the inlet valve 25 to maintain the coil 99 full of liquid refrigerant.

While I have shown a suction pressure controller 105 for controlling the operation of the compressor, it will be understood that I do not limit myself to this, and if desired, a thermostat responsive to the temperature of the compartment cooled by the coil 99 may be employed in place of said suction pressure controller.

30 The system of the present invention therefore operates through its thermostat to maintain the cooling coil 99 flooded at all times during which the compartment temperature is higher than that desired and, by means of the back pressure responsive mechanism defined by bellows 79 and spring 82, operates to close off the suction line by moving valve disc 17 to closed position whenever the back pressure falls to a value indicating that the compartment or cooling coil has been lowered to the proper temperature. In this manner, the system of the present invention operates as a flooded system without the use of the usual expensive float and boiler construction which characterize the ordinary flooded system. 45 The system of the present invention further operates to prevent the back pressure from decreasing below a predetermined point, so that the proper compartment temperature is maintained. Further, this arrangement allows the connecting 50 of a number of cooling coils to a single compressor and maintains the proper back pressure and flooded condition in each of the cooling coils without utilizing the usual electromagnetic suction valve for each cooling coil and the cooperating 55 thermostat located in the associated compartment.

While a specific embodiment of the invention has been herein described, it will readily be seen that many changes can be made without departing from the spirit of the invention, and I therefore intend to be limited only by the following claims. It will be particularly evident that if it is desired to have the thermostat control the expansion or inlet valve 25 without relation to the 65 inlet refrigerant pressure, the levers 38 and 39 can be connected directly to the valve 25, the bellows 30 and springs 35, 47, and 48, and associated parts being eliminated.

I claim:

70 1. The combination with an expansion coil having its high pressure side connected to a suitable supply of liquid refrigerant and its low pressure side connected to a compressor, of a valve for interrupting communication between the expansion coil and compressor, means responsive to

the temperature of the refrigerant on the low pressure side of the expansion coil for operating the valve to maintain said temperature substantially constant, and a device responsive to the pressure of the refrigerant on the low pressure side of the expansion coil for closing the valve, irrespective of the refrigerant temperature, when said pressure falls to a predetermined minimum. 5

2. The combination with an expansion coil having its high pressure side connected to a suitable supply of liquid refrigerant and its low pressure side connected to a compressor, means for reducing the vapor pressure of the refrigerant in said coil, a valve for interrupting communication between the expansion coil and compressor, 15 means responsive to the temperature of the refrigerant on the low pressure side of the expansion coil for operating the valve to maintain the expansion coil normally filled with liquid refrigerant, a device responsive to the pressure of the 20 refrigerant on the low pressure side of the expansion coil for closing said valve at a predetermined pressure irrespective of the amount of liquid refrigerant in the expansion coil, and a mechanical connection between said temperature responsive means and said device. 25

3. The combination with an expansion coil adapted to have its suction end connected to a compressor and its inlet end connected to a suitable supply of liquid refrigerant, of a valve mechanism comprising a casing defining an inlet chamber adapted to be connected to the expansion coil, an outlet chamber and a partition wall therebetween having a valve opening therein, and a valve for closing the valve opening, a thermostat located 30 in the outlet chamber for controlling the valve, a pressure responsive member located in the inlet chamber and moved in valve opening direction by the pressure in the inlet chamber, and means biasing the pressure member to valve 40 closed position for closing the valve when the pressure in the inlet chamber falls to a predetermined minimum. 35

4. The combination with an expansion coil, of an inlet valve for controlling the supply of liquid 45 refrigerant flowing directly to the expansion coil, an outlet valve for controlling the flow of refrigerant from the expansion coil, and means directly responsive to the temperature of the refrigerant leaving the expansion coil for closing both 50 valves as the leaving refrigerant temperature falls to a predetermined minimum.

5. The combination with an expansion coil, of an inlet valve for controlling the supply of liquid refrigerant to the expansion coil, an outlet valve 55 for controlling the flow of refrigerant from the expansion coil, and a single thermostat directly responsive to the temperature of the refrigerant leaving the expansion coil for operating both valves to close the same when the temperature 60 at said thermostat decreases to a value indicating that the expansion coil is substantially filled with liquid refrigerant. 60

6. The combination with an expansion coil, of an inlet valve for controlling the supply of liquid 65 refrigerant to the expansion coil, an outlet valve for controlling the flow of refrigerant from the expansion coil, and a single thermostat responsive to the temperature of the refrigerant leaving the expansion coil mechanically connected to 70 both said valves for moving the same to closed position as the temperature of the refrigerant leaving the expansion coil falls to a value indicating that the expansion coil is substantially filled with liquid refrigerant. 75

7. The combination with an expansion coil having its low pressure side connected to a compressor and its high pressure side connected to a supply of liquid refrigerant, of a unitary valve mechanism, comprising, an outlet valve for controlling the flow of refrigerant from the expansion coil to the compressor, an inlet valve for controlling the flow of liquid refrigerant to the expansion coil, thermostatic means responsive to the temperature of the refrigerant leaving the expansion coil for closing both valves when the temperature of the leaving refrigerant falls to a value indicating that the expansion coil is filled with liquid refrigerant, and means controlled by the pressure on the low side of the expansion coil for closing the outlet valve irrespective of the leaving refrigerant temperature when the low side pressure falls to a predetermined value.

8. The combination with an expansion coil having its low pressure side connected to a compressor and its high pressure side connected to a supply of liquid refrigerant, of a unitary valve mechanism, comprising, an outlet valve for controlling the flow of refrigerant from the expansion coil to the compressor, an inlet valve for controlling the flow of liquid refrigerant to the expansion coil, thermostatic means responsive to the temperature of the refrigerant leaving the expansion coil for closing both valves when the temperature of the leaving refrigerant falls to a value indicating that the expansion coil is filled with liquid refrigerant, and means controlled by the pressure of the liquid refrigerant for permitting the thermostatic means to open the inlet valve only in the event the refrigerant supply pressure is sufficiently high.

9. The combination with an expansion coil having its low pressure side connected to a compressor and its high pressure side connected to a supply of liquid refrigerant, of a unitary valve mechanism, comprising, an outlet valve for controlling the flow of refrigerant from the expansion coil to the compressor, an inlet valve for controlling the flow of liquid refrigerant to the expansion coil, thermostatic means responsive to the temperature of the refrigerant leaving the expansion coil for closing both valves when the temperature of the leaving refrigerant falls to a value indicating that the expansion coil is filled with liquid refrigerant, means controlled by the pressure of the liquid refrigerant for permitting the thermostatic means to open the inlet valve only in the event the refrigerant supply pressure is sufficiently high, and means responsive to the refrigerant pressure on the low pressure side of the expansion coil for closing the outlet valve when the low side pressure falls to a predetermined minimum irrespective of the temperature of the thermostatic means.

10. The combination with an expansion coil having its inlet side connected to a supply of liquid refrigerant, of an inlet valve controlling the flow of refrigerant to the expansion coil and movable in only one direction to prevent such flow, a thermostat responsive to the temperature of the refrigerant leaving the expansion coil and in the path of flow thereof for opening the inlet valve when the leaving refrigerant temperature is above a given minimum, and means responsive to the refrigerant supply pressure for permitting opening movement of the inlet valve by the thermostat only when the supply pressure is above a given minimum.

11. The combination with an expansion coil having its inlet side connected to a supply of

liquid refrigerant, of an inlet valve controlling the flow of refrigerant to the expansion coil, a thermostat responsive to the temperature of the refrigerant leaving the expansion coil for opening the inlet valve when the leaving refrigerant temperature is above a given minimum, means responsive to the refrigerant supply pressure for permitting opening of the inlet valve by the thermostat only when the supply pressure is above a given minimum, an outlet valve controlling the flow of refrigerant from the expansion coil, and means responsive to the pressure of the refrigerant leaving the expansion coil for closing the outlet valve when said pressure falls to a given minimum.

12. A refrigeration valve structure of the class described, comprising, in combination, a casing including an inlet chamber and an outlet chamber with a partition wall therebetween having a valve opening therein, a valve disc for closing the valve opening, a thermostat located in the outlet chamber and connected to the valve for closing the same when the temperature in the outlet chamber falls to a given minimum, a pressure member located in the inlet chamber and adapted to engage the valve for closing the same, and a spring biasing said pressure member toward valve closed position whereby the spring closes the valve if the pressure in the inlet chamber falls to a given minimum.

13. A refrigeration valve structure of the class described, comprising, in combination, a casing means defining high and low pressure inlet and outlet passages, a high pressure valve and a low pressure valve, and a thermostat located in the low pressure outlet passage for closing both the valves when the temperature in the low pressure outlet passage falls to a predetermined minimum.

14. A refrigeration valve structure of the class described, comprising, in combination, a casing defining high and low pressure inlet and outlet chambers, a high pressure valve and a low pressure valve, a thermostat located in the low pressure outlet chamber for closing both the valves when the temperature in the low pressure outlet chamber falls to a predetermined minimum, a pressure responsive member located in the low pressure inlet chamber and adapted to engage the low pressure valve for closing the same, and a spring biasing the pressure member to valve closing position whereby the low pressure valve is closed whenever the pressure in the low pressure inlet chamber falls to a given minimum irrespective of the temperature at the thermostat.

15. A refrigeration valve structure of the class described, comprising, in combination, a casing defining high and low pressure inlet and outlet chambers, a high pressure valve and a low pressure valve, a thermostat located in the low pressure outlet chamber for closing both the valves when the temperature in the low pressure outlet chamber falls to a predetermined minimum, a pressure responsive member responsive to the pressure in the high pressure inlet chamber, and a spring biasing the pressure member to valve closing position whereby the high pressure valve can only be opened by the thermostat if the pressure in the high pressure inlet chamber is sufficiently high.

16. A refrigeration valve structure of the class described, comprising, in combination, a casing defining high and low pressure inlet and outlet chambers, a high pressure valve and a low pressure valve, a thermostat located in the low pressure outlet chamber for closing both the valves

when the temperature in the low pressure outlet chamber falls to a predetermined minimum, a pressure responsive member responsive to the pressure in the high pressure inlet chamber, a spring biasing the pressure member to valve closing position whereby the high pressure valve can only be opened by the thermostat if the pressure in the high pressure inlet chamber is sufficiently high, a second pressure responsive member 5 responsive to the pressure in the low pressure inlet chamber adapted to close the low pressure valve, and a spring biasing the second pressure member to valve closed position whereby the low pressure valve is closed whenever the pressure 10 in the low pressure inlet chamber falls to a given minimum.

17. A refrigeration valve of the class described, comprising, in combination, a casing defining an inlet chamber and an outlet chamber with a partition wall therebetween having a valve opening therein, a valve for closing the valve opening, a pressure member located in the inlet chamber and moved in valve opening direction upon an increase in the inlet chamber pressure, a spring 20 biasing the pressure member in valve closing direction, an extensible connection between the pressure member and valve for maintaining the valve closed irrespective of the position of the pressure member, and a thermostat capable of 25 shortening said extensible connection to open the valve if the pressure member is moved to a predetermined position in valve opening direction.

18. The combination with a cooling coil having its inlet side connected to a supply of liquid refrigerant, of an inlet valve controlling the flow of refrigerant to the expansion coil, a thermostat for controlling said valve to open the same as the temperature to which the thermostat responds rises, and means responsive to the refrigerant 30 supply pressure for permitting opening of said valve by the thermostat only when the supply pressure is above a given minimum.

19. The combination with an expansion coil adapted to have its suction end connected to a compressor and its inlet end connected to a suitable supply of liquid refrigerant, of a valve mechanism comprising a casing defining an inlet chamber adapted to be connected to the expansion coil, an outlet chamber and a partition wall 45 therebetween having a valve opening therein, and a valve for closing the valve opening, a thermostat responsive to the temperature of the refrigerant passing through said valve for controlling the same to close the valve as such temperature falls, a pressure responsive member located in the inlet chamber and moved in valve opening direction by the pressure in the inlet chamber, and means biasing the pressure member to valve 50 closed position for closing the valve when the pressure in the inlet chamber falls to a predetermined minimum.

20. The combination with an expansion coil having its inlet side connected to a supply of liquid refrigerant, of an inlet valve controlling the flow of refrigerant to the expansion coil, said valve being movable in only one direction to close the same and in the opposite direction to open the same, biasing means biasing said valve towards closed position, pressure responsive means responsive to the pressure of the liquid refrigerant working in opposition to said biasing means whereby the valve is freed for opening and closing movements when the pressure of the liquid refrigerant is sufficiently high, and means automatically controlling said valve to open and close 55

the same in response to demands when the valve is thus freed for opening and closing movements.

21. A device of the character described, comprising in combination an expansion coil having its high pressure side connected to a suitable supply of liquid refrigerant and its low pressure side connected to a compressor, a plurality of valves arranged for interrupting communication between said coil and said compressor in a manner to control the quantity of liquid refrigerant in 10 said coil, temperature responsive means arranged for operating said valves to maintain the expansion coil normally filled with liquid refrigerant, and independent pressure responsive means to close one of said valves responsive to a fall in 15 pressure to a predetermined value, and prevent opening of said valve by said temperature responsive means until said pressure has risen.

22. A device of the character described, comprising, in combination, an expansion coil having its high pressure side connected to a suitable supply of liquid refrigerant and its low pressure side connected to a compressor, a plurality of valves arranged for interrupting communication between said coil and said compressor in a manner to control the quantity of liquid refrigerant in 20 said coil, and temperature responsive means arranged for operating said valves to maintain the expansion coil normally filled with liquid refrigerant, said temperature responsive means comprising an expansion chamber containing a temperature responsive volatile fluid.

23. The combination with an expansion coil having its high pressure side connected to a suitable supply of liquid refrigerant and its low pressure side connected to a compressor, means for reducing the vapor pressure of the refrigerant in said coil, means for maintaining said coil substantially full of liquid refrigerant while preventing a flow of liquid refrigerant to said compressor, 35 said means comprising a valve interposed in the path of flow of the refrigerant leaving said evaporator, and a thermostat subjected to the temperature of the outgoing refrigerant, said thermostat being arranged for closing said valve when 40 the temperature of the outgoing refrigerant indicates an approach of liquid refrigerant to said valve and for opening said valve upon an increase in said temperature.

24. In a refrigeration system, an evaporator 50 having an inlet and an outlet, a compressor connected to supply refrigerant to the inlet, and to withdraw refrigerant from the outlet, means for stopping and starting the compressor in accordance with the load on said evaporator, a valve in 55 the outlet, thermostatic means responsive to the temperature of the outgoing refrigerant in control of said valve, a valve in said inlet, and means responsive to the head pressure of said compressor for closing said inlet valve when the compressor is out of operation.

25. In a refrigeration system, in combination, an evaporator, having an inlet and an outlet, means for supplying refrigerant to the inlet of said evaporator, back-pressure reducing means connected to said outlet, an outlet control valve interposed between the outlet and the back-pressure reducing means, means responsive to the temperature of the outgoing refrigerant for actuating said valve, a valve in said inlet, control means for placing said back pressure reducing means into and out of operation, and means controlled by said control means for closing said inlet valve 65 substantially simultaneously with the placing of 70

said back pressure reducing means out of operation.

26. In a refrigeration system, in combination, an evaporator, having an inlet and an outlet, means for supplying refrigerant to the inlet of said evaporator, means for causing evaporation of refrigerant within said evaporator including back-pressure reducing means connected to said outlet, an outlet control valve interposed between the outlet and the back-pressure reducing means, means responsive to the temperature of the outgoing refrigerant for actuating said valve, and automatic means responsive to a condition indicative of operation or non-operation of said back-pressure reducing means for preventing flow of refrigerant when said back-pressure reducing means is out of operation.

27. In a refrigeration system, in combination, an evaporator having an inlet and an outlet, means for supplying liquid refrigerant to said evaporator inlet, back-pressure reducing means connected to said evaporator outlet for withdrawing evaporated refrigerant therefrom, valve means for controlling the flow of liquid refrigerant into said evaporator, means responsive to the pressure of the liquid refrigerant for controlling said valve means, said pressure responsive means being arranged for causing movement of said valve means towards closed position upon a decrease in pressure of said liquid refrigerant, and means responsive to the pressure of the refrigerant in said evaporator for cooperating with said first pressure responsive means in controlling said valve means, said second pressure responsive means being arranged to induce movement of said valve means towards open position upon a decrease in pressure in said evaporator.

28. An expansion valve for refrigeration systems, comprising a valve casing formed to provide a valve chamber and a diaphragm chamber, said chambers being in communication, means for supplying liquid refrigerant to said chambers, a valve means in said valve chamber for controlling the flow of liquid refrigerant from said chamber, diaphragm means in said diaphragm chamber, said diaphragm means being subjected on one side to a pressure to be controlled and on its other side to said liquid refrigerant, means associated with said diaphragm means and said valve means for actuating said valve means by movements of said diaphragm means, and second diaphragm means in said diaphragm chamber, said second diaphragm means being associated with said first diaphragm means in a manner to prevent changes in pressure of said liquid

refrigerant from influencing said first diaphragm means.

29. An expansion valve for refrigeration systems, comprising a valve casing formed to provide a valve chamber and a diaphragm chamber, a partition wall between said valve chamber and said diaphragm chamber, an opening in said partition wall for providing restricted communication between said valve chamber and said diaphragm chamber, means for supplying liquid refrigerant to said valve chamber, valve means in said valve chamber for controlling the flow of liquid refrigerant from said chamber, a diaphragm in said diaphragm chamber, said diaphragm being subjected on one side to a pressure to be controlled and on its other side to said liquid refrigerant in a manner to cause movement of said diaphragm upon change in said pressure to be controlled, and means extending from said diaphragm through the opening in said partition wall to said valve means for actuating said valve means by movements of said diaphragm.

30. An expansion valve for refrigeration systems, comprising a valve casing formed to provide a valve chamber and a diaphragm chamber, said chambers being in communication, means for supplying liquid refrigerant to said chambers, a valve means in said valve chamber for controlling the flow of liquid refrigerant from said chamber, a diaphragm in said diaphragm chamber, said diaphragm being subjected on one side to a pressure to be controlled and on its other side to said liquid refrigerant, means associated with said diaphragm and said valve means for actuating said valve means by movements of said diaphragm, seal-off diaphragm means in said diaphragm chamber, said seal-off diaphragm means having one portion movable with said first mentioned diaphragm and a second portion attached to said valve casing in a manner to seal off the refrigerant in said diaphragm chamber from atmosphere, and a biasing spring for said first mentioned diaphragm, said biasing spring being located exteriorly of said seal-off diaphragm means.

31. An expansion valve for refrigeration systems, comprising a valve casing, valve means in said casing for controlling the flow of refrigerant from said valve casing, and a diaphragm assembly for actuating said valve means also located in said valve casing, said diaphragm assembly comprising a pair of aligned cylindrically shaped diaphragms having corrugated side walls, and means within said diaphragms for guiding expansion and contraction movements of each with respect to the other.

PAUL F. SHIVERS.
